US0D1046332S

(12) **United States Design Patent** (10) **Patent No.:** **US D1,046,332 S**
Mei (45) **Date of Patent:** **** Oct. 8, 2024**

(54) **TOILET PLUNGER**

(71) Applicant: **SHENZHEN ZHHUI CHUANGXIANG TECHNOLOGY CO., LTD.**, Shenzhen (CN)

(72) Inventor: **Xu Mei**, Shenzhen (CN)

(73) Assignee: **SHENZHEN ZHHUI CHUANGXIANG TECHNOLOGY CO., LTD.**, Shenzhen (CN)

(**) Term: **15 Years**

(21) Appl. No.: **29/774,267**

(22) Filed: **Mar. 15, 2021**

(51) **LOC (14) Cl.** **15-05**

(52) **U.S. Cl.**

USPC **D32/14**; D32/35; D6/524

(58) **Field of Classification Search**

Reloader Toilet Bowl Plunger Holder Bathroom, available in Amazon.com, date first available Sep. 22, 2021 [online], [site visited Dec. 21, 2023], Available from the internet URL: <https://www.amazon.com/Toilet-Bowl-Plunger-Holder-Bathroom/dp/B09VXK257Q> (Year: 2021).*

Primary Examiner — Jennifer Rivard

Assistant Examiner — Jennylo M Binas

(57) **CLAIM**

The ornamental design for a toilet plunger, as shown and described.

DESCRIPTION

FIG. 1 is a perspective view of a toilet plunger showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
